LOCOMOTIVE ASH PAN

Anders Gustaf Gunnar Salenius, Narberth, Pa., assignor to The Pennsylvania Railroad Company, Philadelphia, Pa., a corporation of Pennsylvania

Application April 24, 1941, Serial No. 390,032

7 Claims. (Cl. 110—167)

This invention has reference in its broader aspects to receptacles or pans commonly located below fire-grates for the collection of ashes to be periodically discharged or dumped, whenever desirable or expedient. Receptacles or ash pans of the referred to species customarily include one or more hoppers each having an individual slideable, or a swinging door, the latter sometimes supported off-center to obtain a wedging effect on its seat when closed, and associated means whereby said door or doors are independently or collectively operable for discharge of the collected ashes. The present invention has more particular reference to locomotive ash pans of the type wherein the several hoppers have pivoted curved section doors for individual or multiple actuation. Such means have proven generally satisfactory excepting that in order to prevent the doors coming too close to the rails, under certain conditions, when they are opened, it has been found necessary to reduce the depth of the hoppers which, disadvantageously, affects the capacity of the ash-pan, with resultant more frequent necessity for, and often inconvenient, dumping of the contents.

The primary aim of the present improvements is to overcome the above noted disadvantage by arranging the hopper closure door so that it operates within restricted limits; or, in other words, by mounting the door so that its axis for pivotal movement is above the curved seating surface, and locating said surface as low as possible so that the door may operate, at all times, in close proximity to the minimum, permissible, track clearance level.

Another aim of this invention is to pivot the hopper curved door in a novel manner, so that as it approaches the fully closed position it is eccentrically forced upwards, or jammed, against the hopper seat, with provision of a substantially leak-proof joint or seal.

A further aim is to furnish a locomotive ash-pan and discharge hoppers, of the largest possible capacity, with curved-section closure doors for said hoppers, so constructed and coordinated for operation as to effectively maintain, at all times, the necessary clearance imposed by other parts of the locomotive and the track.

While the foregoing definitions are indicative, in a general way, of the aims of this invention, other objects, with ancillary advantages, will be evident to those skilled in the art upon a full understanding of the construction, arrangement and operation of the means hereinafter disclosed; but it will also be appreciated that said

invention is susceptible of other embodiments, or structurally modified forms, coming equally within the terms of the concluding claims.

In the accompanying drawings:

5 Fig. 1 is a part sectional and part side elevation of the lower portion of a locomotive fire-box and ash pan embodying the present improvements.

10 Fig. 2 is a plan section taken approximately as indicated by the angle arrows II—II in Fig. 1.

Fig. 3 is a part vertical section and part elevation as viewed substantially on the staggered plane III—III of Fig. 2.

15 Fig. 4 is an end elevation as viewed from the left-hand side of Fig. 1, or looking towards the right thereof.

Fig. 5 is a vertical cross-section on the staggered plane V—V in Fig. 1; and,

20 Fig. 6 is a fragmentary section taken as indicated by the angle arrows VI—VI in Fig. 1.

25 In describing the form of this invention exemplified by the above captioned drawings here-with, specific terms will be employed for the sake of clarity, but it is to be understood the scope of said invention is not thereby limited; each such term being deemed to embrace all equivalents which perform the same function for an analogous purpose.

30 Referring to the drawings, the reference character 7 designates the grate of a conventional type locomotive fire box, 8 the supporting frame therefor, and 9 the mud ring. Supported as by suitable hangers 10, as well as by main frame 11, are the wing plates 12 which extend inwardly of said beams for attachment, as by bolts 13, of the angled edges 14 of the ash pan side plates 15. The respective rear and front end ash pan end walls are designated 16, 17 and they are secured to the side plates 15 in any appropriate manner, for example by angle sections 18. The side plates 15 are, preferably, each formed in two parts connected together by bolts 19 and lap pieces 20 in an obvious manner, while it is to be noted the rear and front ash pan walls 16, 17 are also secured in position by bolts 21, so that the ash pan is rendered detachable when necessary.

35 Each side plate 15 is appropriately contoured along the lower edge and inwardly stepped at 22, Figs. 4 and 5, to define a rear and consecutive 40 forwardly spaced intermediate hoppers 23, 24 respectively, for application thereto of the door frames 25. Each door frame 25, it will be remarked, preferably embodies spaced rear and front inwardly inclined walls 26 with polygonal 45 shaped attaching side walls 27, the lower edges

of the latter walls extending below the level of the former walls and being curved to provide a circular seat 28, in vertical section longitudinally of the ash pan. The bottom plates 29 of the ash pan, intervening the respective hoppers 23, 24 are extended down between the frame side walls 27 and are suitably attached to the frame rear and front walls 26. The axis of curvature for the circular seat 28 is a point centrally and vertically above said seat, as conventionally indicated at c in Fig. 3 for a purpose hereafter explained.

The respective hopper doors 30 are of a complementary curvature in vertical section, to that of the seat 28, and they are provided with apertured lugs 31 to which the lower ends of supporting links 32 are attached by hinge pins 33, said links being in turn sustained by laterally projecting studs 34 fulcrumed in notches 35 of bearing elements 36 forwardly projecting from laterally directed brackets 37, integral with or rigidly secured to the hopper frame side walls 27. It is to be noted the curvature centers of the stud bearing notches 35 are located offset or forwardly relative to the centers c and, preferably, horizontally co-planar with the latter. This arrangement for supporting the doors 30 positively ensures said doors being forced, at the time of final closure, up against the seats 28 with an, obviously, effective seal thereto; while the foremost door lugs 31 project downwards with the associated supporting links operating through slots 38 in the door 30, whereas the remaining lugs 31 on the other doors 30 project upwardly for reasons hereafter explained.

The several doors 30 are each provided with a pair of rearwardly positioned upstanding lugs 39 fitted with axis pins 40, and in order that each consecutive pair of said doors may be simultaneously opened and closed, connecting links 41 have their forward ends pivoted on the pins 40, with the rear ends of said links similarly attached at 42 to the upper parts of rocker members 43 associated with the rearwardly related doors 30, said members in turn having their lower ends pivoted to the axis pins 40 of the second mentioned doors, as clearly understandable from Figs. 1 and 3 more particularly, so that the doors 30 of the hopper 23 and the forwardly adjacent hopper 24 are operatively coordinated, and the doors 30 of the foremost pair of hoppers 24 are correspondingly coupled together, reading from the left towards the right-hand of Figs. 1-3.

The consecutively coupled pairs of doors 30 are under operative control of equalizer rods, the respective forward components 44, 45 whereof are fulcrumed at 46 to the aforesaid rocker members 43 intermediate the axis pins 40 and the rear pivots 42; while the rear components 47, 48 of said equalizer rods are similarly coupled at 49, 50 to the lower ends of actuator levers 51, 52. The actuator levers 51, 52 are conveniently mounted on transverse rock shafts 53, 54 rotatively journaled in bearing elements 55, rigidly secured by fastening means 56 to the outboard sides of the main frame 11, hereinbefore mentioned. In order to limit the angular movement of the actuator levers 51, 52, use is made of a composite control quadrant 57 embodying spaced walls 58 and a separator piece 59, between which walls and separator piece the upper portions of said actuator levers are normally located; or, during the time that the hopper doors 30 are closed. Rigid with the control quadrant 57 are overhanging rectangularly related fork hangers 75

60, 61 affording suspension for counter-balanced reversely active pivotal dogs 62, each embodying a stop portion 63, see to best advantage in Fig. 6; said dogs being respectively coactive with the levers 51, 52 for locking the latter against accidental release. It will now be readily understood that in order to release the outer lever 52, for example, said lever must be pushed forwardly or clockwise by aid of its cranked portion 64, whereupon the associated dog 62 is manually rocked on its pivot 65 (with angular retraction of its stop portion 63 from abutment below the hanger 61) from the full line position of Fig. 6 to the dot-and-dash location in the same figure, when the lever 52 will be freed for counter-clockwise movement until it contacts the movement-limiting end 66 of the quadrant 57, with incidental swinging of the operatively coordinated foremost pair of doors 30 to the open position shown in Fig. 3. On the other hand, when the inner actuator lever 51 is to be correspondingly moved relative to the axis of the shaft 53 the same operations take place with the exception that the associated dog 62 is turned counter-clockwise, on its pivot 67, to angularly swing the stop portion 63 thereof away from abutment below the hanger 60. Obviously, on reverse movement of the respective actuator levers 51, 52, to effect closure of the hopper doors 30, the dogs 62 will be rocked by said levers, on the respective pivots 65, 67, and automatically swing back into active locking position as clearly understandable from Fig. 6.

Referring again to the bearing elements 36, for the respective door supporting links 32, it is to be particularly noted that the notch or open ended bearing slot 35 is partially closed in by a stud pin 69 having a reduced end 70 screw-threaded through a hole in the laterally directed bracket 37, said bolt being secured against rotation by a lock nut 71. Thus it will be seen that the respective link studs 34 are prevented from accidental dislodgment, whereas a simple means is provided for the ready release or removal of an individual door 30 when desirable or expedient, as obvious to those conversant with the art. In addition it is to be further noted that laterally projecting angle pieces or relative motion limiting or abutment stops 72 are provided in the region of the hinge connections 33 of the supporting links 32 to the door lugs 31, where said lugs are above the doors 30. The stops 72, it will be remarked, serve to maintain the links 32 and door lugs 31 in substantial alignment while providing for slight oscillatory movement of the door 30 for a purpose later on herein again referred to. A rigid collar 73 is also provided on each equalizer rod rear component 47, 48 to positively ensure direct thrust of the respectively associated front components 44, 45 during movement to open the doors 30. A stop piece 75 is applied in each fork-shaped end of the components 44, 45, adjacent to the rockers 43, to prevent possible collapsing of said rockers in case the doors operated by the levers 41 should develop greater opening resistance than the respectively coupled rearward door 30.

The operation of the improved hopper doors 30 will be obvious from the foregoing disclosure, but it is desired to emphasize the fact that incidental to supporting said doors by the links 32 in the manner described with the axes of the fulcrum studs 34 substantially stationary, and those of the hinge pins 33 being retained in relative pendulous radial alignment therewith by means of the abutment stops 72, each door 30 is con-

strained to a definite path of movement. In other words, on reference to Figs. 1 and 3 more particularly, and assuming all of the hopper doors 30 are closed to the seats 28, it will be apparent that as the actuator lever 52 is drawn towards the quadrant end 66 the equalizer rear component 48 will be forwardly moved and, by means of the collar 73, the forward component 45 is similarly advanced with a direct thrust imparted to the associated rocker 43. The thrust thus imparted compresses the equalizer rod springs 74 for reaction to effect an initial slight angular movement of the rocker members 43 sufficient to release the foremost pair of doors 30 from sealing engagement with the hopper seats 28 followed by circular progression of said doors along a path conformatory with an arc struck from the axis of the link supporting studs 34. The action just described clearly permits the hopper frames 25 being located much lower relative to a railroad trackway, as it is quite obvious that only just sufficient clearance is needed for the definite and direct pathway of travel for the doors 30 in close circular proximity to the hopper seats 28. On the other hand, as the doors 30 approach closed position relative to the seats 28, a reverse action of the parts above explained results in a slight upward jamming movement being imparted to the doors with consequent sealing abutment thereof against said seats 28.

From the foregoing the merits and advantages of this invention will be thoroughly appreciated by those acquainted with the art, while it is to be understood that the form herein disclosed is susceptible of detail changes in adapting the same to different types of locomotive and other fire boxes, without departing from the essentials and scope of the following claims, or the sacrifice of any of the advantages hereinbefore pointed out.

Having thus described my invention, I claim:

1. The combination with a locomotive fire box of an ash pan including spaced hoppers, an outlet at the bottom of each hopper having a seating surface at opposite sides curved to an arc of a circle struck from a center vertically above and medially within the confines of said hopper sides, a correspondingly curved door adapted to seat against said outlet, hinged suspension elements for the door having aligned pivot axes planarly offset relative to the seating surface center of curvature aforesaid and also having hinge connections to said door, and means for closing or opening the several doors along curved paths of movement eccentric to the seating surface curvatures.

2. The combination with a locomotive fire box of an ash pan including spaced hoppers having substantially parallel side walls, an outlet at the bottom of each hopper having a seating surface curved to an arc of a circle struck from a center vertically above and medially within the confines of the respective hopper side walls afore-

said, a correspondingly curved door adapted to seat against the hopper outlet, hinged suspension elements for the door having aligned pivot axes horizontally offset relative to the seating surface center of curvature aforesaid and also having hinge connections to said door, means normally holding the suspension elements in radial alignment but permitting limited oscillation of the door, means operative to close or open the several doors along individual eccentric paths of movement close to the outlet seating surface curvatures, and means for imparting slight inward radial movement to the door to effect sealing coaction thereof with the associated seating surface, said means also serving to initiate opening of the door.

3. The combination of claim 2, wherein the ash pan side walls are made in two parts connected end to end, each said part having the upper edge portion inwardly angled for attachment to the fire box, and said walls are inwardly stepped in the region of the spaced hoppers.

4. The combination of claim 2, wherein each hopper outlet consists of a rectangular frame embodying front and rear downwardly converging walls and polygonally-contoured side walls, a bracket projects laterally outward from the upper portion of each hopper side wall with a vertically notched portion paralleling said side wall, said notch being open at the upper end to afford pivotal support for the associated hinged door suspension element, and means are carried by each bracket aforesaid to partly close the open end of the vertical notch.

5. The combination of claim 2, wherein each hinged suspension element comprises a link with an upper fulcrum stud, a pin at the lower end of said link, and an apertured lug on the associated curved door having hinge connection to said link pin, and reversely directed obtuse angled abutment stops projecting from the hopper side walls mutually coact with such hinge connection to retain the link substantially stationary while permitting the curved door to have a relatively slight hinge movement.

6. The combination of claim 2, wherein the means effective to close or open the several doors comprise equalizer rods with associated collars and reactive means effective to impart positive thrust in one direction, said rods being operatively coupled at their forward ends to a pair of consecutive doors, a quadrant and actuator levers control reciprocation of said equalizer rods, and counter-weighted pivotal dogs carried by the quadrant coact with said actuator levers to lock them against accidental movement when the doors are closed.

7. The combination of claim 1, in which the spaced hoppers extend downwardly into close proximity to the minimum track clearance level, whereby the dumping capacity of the respective hoppers is substantially increased.

ANDERS GUSTAF GUNNAR SALENIUS.
